DECORATIVE ENCLOSURE FOR A LIGHTING FIXTURE

Bernard Aronson, Cherry Hill, N.J., assignor to Sim-Kar
Lighting Fixture Co., Fort Washington, Pa.

Filed Jan. 16, 1975, Ser. No. 541,580

Term of patent 14 years

Int. Cl. D26—05

FIG. 1.

FIG. 2.

FIG. 3.

FIG. 4.

FIG. 5.

FIG. 6.

FIG. 7.

FIG. 8.

FIG. 1 is a perspective view of a decorative enclosure for a lighting fixture embodying my new design;

FIG. 2 is a plan view thereof;

FIG. 3 is an end elevational view thereof;

FIG. 4 is a front elevational view thereof;

FIG. 5 is an inverted plan view thereof;

FIG. 6 is a sectional view taken along line 6—6 of FIG. 5;

FIG. 7 is a perspective view of a modified embodiment of my new design; and

FIG. 8 is a perspective view of another modified embodiment of my new design.

I claim:

The ornamental design for a decorative enclosure for a lighting fixture, substantially as shown and described.
